LINE INDICATING COPY HOLDER

Arthur L. Slee, San Francisco, Calif.

Application July 6, 1936; Serial No. 89,102

15 Claims. (Cl. 120—34)

My invention relates to improvements in line-indicating copy holders wherein a pair of similar, slidably superimposed sheets operate in conjunction with a line indicator movably superimposed upon one of said sheets and provided with means for engaging said sheets to permit movement of said indicator in one direction only, relatively to said sheets, whereby said indicator may be moved intermittently over copy upon said sheets when said sheets are intermittently reciprocated, one upon the other.

The primary object of the present invention is to provide a new and improved line-indicating copy holder.

Another object is to provide a new and improved device of the character described which may be easily and economically constructed either from sheets of common pasteboard, to provide an extremely cheap device, or from sheets of a more durable material, such as thin sheet metal or the like, to provide a more durable device, either material providing a device of extremely economical construction and having a maximum efficiency and ease of operation.

A further object is to provide, in combination with a device of the character set forth, an extremely simple, efficient and easily operable device for regulating the amount of movement of a line indicator to equal single, double, or even triple spacing of a standard typewriter.

A still further object is to provide a new and improved line-indicating copy holder having many of the advantages and utilities of the expensive devices now in use, but one which may be produced at a greatly reduced cost and having a greater ease of operation.

A still further object is to provide a new and improved line-indicating copy holder that will be less bulky and lighter in weight than copy holders now in use, to permit a greater ease of transportation from one position to another, to promote a greater range of utility and a more universal use of copy holders.

I accomplish these and other objects by means of the improved device disclosed in the drawings forming a part of the present application, and in which—

Fig. 1 is a partly broken front elevation of my improved copy holder;

Fig. 2 is a side elevation thereof;

Fig. 3 is an enlarged sectional view taken on line 3—3 of Fig. 1, in the direction indicated;

Fig. 4 is an enlarged sectional view taken on line 4—4 of Fig. 1, in the direction indicated;

Fig. 5 is a broken sectional view taken on line 5—5 of Fig. 1, in the direction indicated;

Figs. 6 and 7 are detail views;

Fig. 8 is a modified form of the sliding connection disclosed in Fig. 3;

Fig. 9 is a view similar to Fig. 4, disclosing a modified form.

Referring to the drawings:

The numeral 1 is used to designate what I term, for convenience, a base sheet which may be formed of either common pasteboard or a more durable, thin sheet material, such, for instance, as sheet metal. The base sheet 1 is held, for convenience in reading as well as for operation, slightly slanted or substantially upright by any suitable easel or support 2, as disclosed in Fig. 2 of the drawings.

The base sheet 1 is provided with vertically disposed slots 3, a horizontal slot 4 near the base thereof, notches 6 in both side edges thereof, and a tab 7 for engaging the easel or support 2, to retain said base sheet in a slightly slanted or substantially upright position.

What I term, for convenience, a copy sheet 8, for holding copy 9, is slidably superimposed for limited vertical reciprocating movement upon the base sheet 1 and is also formed of common pasteboard or thin sheet metal, and is provided with notches 6 and with means for slidably engaging the slots 3 of the base sheet 1, to limit reciprocal movement of said sheet 8 upon said base sheet 1, said means comprising either ordinary, brass paper fasteners 11, as disclosed in detail in Fig. 3 of the drawings, or struck up lugs or tabs 12, as disclosed in full lines in Fig. 8 of the drawings, or any other suitable device by means of which said copy sheet 8 may be slidably superimposed for limited reciprocal movement upon the base sheet 1.

The copy sheet 8 is provided at its lower edge with a ledge or shelf 14 upon which rests the lower edge of the copy 9, this ledge also serving as a means of operation, as hereinafter more fully set forth.

A line indicator 16, also cut from flat or sheet material, is horizontally and movably superimposed upon the copy sheet 8 and is provided with a longitudinally disposed slot 17, through which the line to be copied, not shown, on the copy 9, is exposed, the longer edges of said slot 17 being continued beyond the vertical edges of sheet 8 to form inwardly projecting tabs 18. The slot 17 is substantially the same length as the width of the sheets 1 and 8 so that the inner ends of said tabs 18 form guides for engaging the edges of

5

50

55

said sheets 1 and 8, when said tabs 18 are sprung from the plane of said indicator, as hereinafter explained, to limit longitudinal movement of said indicator upon the sheets 1 and 8.

5 Upwardly pointed metal points or detents 19, 19' are mounted upon the back of the indicator 16 and also upon the front faces of the tabs 18, respectively, the detents 19 upon the back surface of the indicator 16 proper engaging the front surface of the copy sheet 8, while the detents 19' upon the tabs 18 engage the back or opposite surface of the base sheet 1, to prevent upward movement of said indicator 16 relatively to said sheets, as disclosed in detail in Fig. 4 of the drawings.

10 When the device is made of pasteboard the detents will effectively engage said sheets 1 and 8 and prevent upward movement of the indicator 16 thereon while readily permitting a downward movement of said indicator. If it is desired, the detents 19, 19' may be slightly offset from each other in their downward paths so that when said indicator has reached its lowermost position and is resting upon the ledge or shoulder 14 of the copy sheet 8, the detents 19' will register with the lower registering notches 6 of the sheets 1 and 8, to readily permit the detents 19' to disengage the back of the base sheet 1.

15 When the device is made of sheet metal not effectively engaged by said detents 19, 19', suitable apertures 21, arranged at spaced intervals equal to the standard spacing of typewriters, may be provided parallel to both edges of both sheets 1 and 8, as shown in section in Fig. 9 of the drawings. The detents 19, 19' will then intermittently engage successive apertures instead of merely engaging the surfaces of their respective sheets, when the indicator 16 is moved downwardly as hereinafter described.

20 A plate 22 is bent upwardly from a slide 23 resting upon the base of the easel or holder 2 and has an integrally formed tab 24 slidably engaging the horizontal slot 4 in the lower portion of the base sheet 1, as disclosed in Figs. 1, 2, 45 and 5 of the drawings, to limit movement of said plate 22. The plate 22 is interposed between the lower ends of the sheets 1 and 8 and is provided with an aperture 26 through which the lower fastener 11 or tab 12, as the case may be, 50 extends before passing through the lower slot 3 of the base sheet 1.

25 The lower edge of the aperture 26 intercepts the lower edge of the fastener 11, or tab 12, when the sheet 8 is moved downwardly and limits such downward movement, which is equivalent to double spacing upon a typewriter. The aperture 26 is provided with a shoulder 27 which, when the slide 23 is moved to the proper extreme position, intercepts the fastener 11, or tab 12, 60 when the same has moved a distance equal to a single space upon a typewriter. By means of this slide the copy sheet 8 and indicator 16 may be moved for either single or double spacing, according to the nature of the matter being copied, 65 suitable indicia being provided as at 28 to indicate for which, single or double spacing, the adjustable device is set.

70 When the device is made of pasteboard an ordinary elastic rubber band 31 is stretched preferably between the lower fastener 11, or tab 12, and the tab 1 upon the back of the base sheet 1, as disclosed in Fig. 2 of the drawings, in full lines, and indicated in dotted lines in Fig. 1.

75 This elastic rubber band 31 normally retains the copy sheet 8 in its uppermost position upon

the base sheet 1 and instantly returns said sheet to such position after having been moved downwardly and released.

When the device is made of a heavier and more durable material, such as sheet metal or the like, a suitable spring, not shown, or stronger and larger elastic bands may be substituted for the ordinary rubber band shown, in order to more promptly return the heavier copy sheet to its upper position.

10 In operation:

15 The copy 9 is placed upon the copy sheet 8 with the lower edge of said copy 9 resting upon and supported by the ledge 14 upon the lower end of the copy sheet 8, as disclosed in Fig. 1 of the drawings, with the upper corners of said copy 9 inserted through inclined slots 32, in order to prevent said copy 9 from moving laterally and interfering with the path of progress of the detents 19 engaging the face of the copy sheet 8. 20

25 The indicator 16 is then superimposed upon the copy sheet 8 and over the copy 9 thereon near the top of said sheet 8 as disclosed in dotted lines in Fig. 1 of the drawings. This will place the detents 19', projecting from the inner ends of the tabs 18, directly opposite the upper registering notches 6 of the aligned sheets 1 and 8 so that when said tabs 18 are sprung backwardly beyond the plane of the indicator 16, and said indicator is moved to bring said detents 19' below said notches 6, and the pressure on the tabs 18 is then released, the slight tension of said tabs 18 will move the detents 19, 19' into engaging relation with the front of the copy sheet 8 and the back of the base sheet 1, respectively, and 30 normally prevent movement of the indicator 16 in either direction and positively in an upwardly direction, by reason of the upward inclination of said detents 19, 19'.

35 When the device is formed of metal the indicator 16 is moved as above described until the detents 19, 19' engage their respective apertures 21 which serve as rack teeth in promoting the downward progress of the indicator 16.

40 The indicator 16 is now moved downwardly over the copy 9 until the first line thereon to be copied is exposed through the slot 17. After said line has been copied a slight downward pressure on the ledge or shelf 14 will move the copy sheet 8 downwardly, against the tension of the elastic rubber band 31 until the lower edge of the fastener 11, or tab 12, engages the lower edge of the aperture 26 in the member 22 interposed between the sheets 1 and 8, or the shoulder 27 of said aperture, and limits or prevents further downward movement of said sheet 8. During this downward movement of said copy sheet 8 the said sheet is engaged by the upwardly slanted bars or detents 19 and the indicator 16 is moved downwardly an equal distance with said copy sheet 8, which distance is equal to a single or double typewriter space, and exposes through the longitudinal slot 17 the next lower line on the copy 9. 50

55 When the pressure on the ledge or shelf 14 is removed the tension of the elastic band 31 will instantly return the copy sheet 8 to its uppermost position, as limited by the length of the slots 3, and during this movement the detents 19 will engage the back of the base sheet 1 and 60 prevent a return of the indicator 16 with said return movement of the copy sheet 8.

65 This process is repeated after each line has been exposed through the slot 17 and copied, until the lower edge of the indicator 16 rests 70

upon the shelf or ledge 14 of the sheet 1, in which position the detents 19' will register with the lower registering notches 6 so that said indicator may be removed, the copy 9 removed, and the process repeated with the next sheet to be copied.

5 The detents 19, 19', when the device is formed of pasteboard, may be of any suitable material sufficiently hard and sharp to effectively engage the surfaces of the sheets 1 and 8 and normally prevent movement of the indicator 16.

10 Having described my invention I claim—

1. A copy holder comprising a base sheet; a copy sheet slidably superimposed upon said base sheet; a line indicator superimposed upon the copy sheet; and means for engaging both sheets to normally hold said indicator against movement relatively to said sheets and for engaging one of said sheets, when moved upon the other, and substantially releasing said other sheet to move said indicator with said moved sheet.

15 2. A copy holder comprising a base sheet; a copy sheet slidably superimposed upon said base sheet; a line indicator movably superimposed upon the copy sheet; and means upon the indicator for engaging both sheets to normally hold said indicator against movement relatively to said sheets and for engaging one of said sheets, when moved upon the other, and substantially releasing said other sheet to move said indicator with said moved sheet; and means for normally returning said moved sheet to original position upon said other sheet.

20 3. A copy holder comprising a base sheet; a copy sheet slidably superimposed upon said base sheet; a line indicator superimposed upon said sheets; and means secured to said indicator for engaging both sheets to normally hold said indicator against movement thereon, and for engaging one sheet when the same is moved upon the other in one direction and substantially releasing said other sheet to move said indicator with said moved sheet, and for substantially releasing said moved sheet and for engaging said other sheet when said moved sheet is moved in an opposite direction, to prevent return of said indicator with said moved sheet.

25 4. A copy holder comprising a base sheet; a copy sheet slidably superimposed upon said base sheet; a line indicator movably superimposed upon both of said sheets; and means secured to said indicator for engaging both sheets to normally hold said indicator against movement thereon, and for engaging one sheet when the same is moved upon the other in one direction and substantially releasing said other sheet to move said indicator with said moved sheet, and for substantially releasing said moved sheet and for engaging said other sheet when said moved sheet is moved in an opposite direction, to prevent return of said indicator with said moved sheet; and elastic means for normally returning said moved sheet to original position upon said other sheet.

30 5. A copy holder comprising a base sheet; a copy sheet slidably superimposed upon said base sheet; a line indicator movably superimposed upon said copy sheet; and detents secured to said indicator and engaging both sheets to normally prevent movement of said indicator relatively to said sheets, certain of said detents engaging said copy sheet and the remaining detents substantially releasing said base sheet when said copy sheet is moved in one direction thereon, to move said indicator with said copy sheet, said certain detents substantially releasing said copy

sheet and said remaining detents engaging said base sheet when said copy sheet is returned to original position upon said base sheet, to prevent said indicator from being returned with a return movement of said copy sheet on said base sheet.

35 6. A copy holder comprising a base sheet; a copy sheet slidably superimposed upon said base sheet; a line indicator movably superimposed upon said copy sheet; detents secured to said indicator for engaging both sheets to normally prevent movement of said indicator relatively to said sheets, certain of said detents engaging said copy sheet and the remaining detents substantially releasing said base sheet when said copy sheet is moved in one direction thereon, to move said indicator with said copy sheet, said certain detents substantially releasing said copy sheet and said remaining detents engaging said base sheet when said copy sheet is moved in an opposite direction to prevent said indicator from being returned with said copy sheet in said opposite direction; and elastic means connected to both sheets for normally returning said copy sheet in said opposite direction.

40 7. A copy holder comprising a base sheet; a copy sheet slidably superimposed for reciprocal vertical movement upon said base sheet; a line indicator movably superimposed for vertical movement upon said copy sheet; and upwardly pointed detents secured to said indicator and engaging both sheets to normally prevent movement of said indicator relatively to said sheets, certain of said detents engaging said copy sheet and the remaining detents substantially releasing said base sheet when said copy sheet is moved downwardly thereon to move said indicator with said copy sheet, said remaining detents engaging said base sheet and said certain detents substantially releasing said copy sheet when the same is moved upwardly to prevent upward movement of said indicator.

45 8. A copy holder comprising a base sheet; a copy sheet movably superimposed for reciprocal vertical movement upon said base sheet; a line indicator movably superimposed for vertical movement upon the copy sheet; upwardly pointed detents secured to said indicator and engaging both sheets to normally prevent movement of said indicator thereon, certain of said detents engaging said copy sheet and the remaining detents substantially releasing said base sheet when said copy sheet is moved downwardly thereon to move said indicator with said copy sheet, said remaining detents engaging said base sheet and said certain detents substantially releasing said copy sheet when the same is moved upwardly to prevent upward movement of said indicator with said upwardly moving copy sheet; and means for limiting movement of said copy sheet upon said base sheet.

50 9. A copy holder comprising a base sheet; a copy sheet slidably superimposed for reciprocal vertical movement upon said base sheet; a line indicator movably superimposed for vertical movement upon said sheets; and upwardly pointed detents secured to said indicator and engaging both sheets to normally prevent movement of said indicator on said sheets, certain of said detents engaging said copy sheet and the remaining detents substantially releasing said base sheet when said copy sheet is moved downwardly thereon to move said indicator downwardly with said copy sheet, said remaining detents positively engaging said base sheet and said certain detents

substantially releasing said copy sheet when the same is returned upwardly to prevent upward movement of said indicator with said copy sheet; and means for regulating the degree of downward movement of said copy sheet upon said base sheet, to permit said indicator to be moved selected distances.

10. A copy holder comprising a substantially upright pasteboard base sheet; a pasteboard copy sheet slidably superimposed for limited vertical movement upon said base sheet; a horizontally disposed pasteboard line indicator movably superimposed upon said sheets; and upwardly inclined and pointed detents secured to said indicator and engaging said sheets to normally prevent movement of said indicator thereon, certain of said detents positively engaging said copy sheet and the remaining detents substantially releasing said base sheet when said copy sheet is moved downwardly on said base sheet to move said indicator downwardly with said copy sheet, said certain detents substantially releasing said copy sheet and said remaining detents engaging said base sheet when the copy sheet is returned upwardly to prevent upward movement of said indicator with said copy sheet.

11. A copy holder comprising a substantially upright pasteboard base sheet; a pasteboard copy sheet slidably superimposed for limited vertical movement upon said base sheet; a horizontally disposed pasteboard line indicator movably superimposed upon said sheets; upwardly inclined and pointed detents secured to said indicator and engaging said sheets to normally prevent movement of said indicator on said sheets, certain of said detents positively engaging said copy sheet and the remaining detents substantially releasing said base sheet when said copy sheet is moved downwardly thereon, to move said indicator downwardly with said copy sheet, said certain detents releasing said copy sheet and said remaining detents engaging said base sheet when the copy sheet is returned to its uppermost position to prevent return upwardly of said indicator with said copy sheet; and means for normally retaining said copy sheet in its uppermost position.

12. The combination with a copy holder comprising a pair of superimposed and slidably connected sheets, of a line indicator movably superimposed upon said sheets and having tabs formed integral therewith; means mounted upon said indicator for engaging one of said sheets to prevent movement of said indicator in one direction on said sheet; and means mounted upon said tabs and urged by the tension of said tabs, when sprung beyond the plane of said indicator to engage the other sheet and prevent movement of said indicator thereon in the same direction prevented by said first mentioned means relatively to said first mentioned sheet.

13. The combination with a copy holder comprising a pair of superimposed and slidably connected pasteboard sheets, of a pasteboard line indicator movably mounted on said sheets and having tabs formed integral therewith; upwardly inclined points mounted upon said indicator for engaging one of said sheets for preventing movement of said indicator in one direction thereon; and similar upwardly inclined points secured to said tabs and urged by the tension of said tabs, when the same are sprung beyond the plane of said indicator, to engage the other sheet and prevent movement of said indicator in the same direction upon said other sheet prevented by the first mentioned points upon the first mentioned sheet.

14. A copy holder comprising a substantially upright pasteboard base sheet having vertically disposed slots therein; a similar pasteboard copy sheet superimposed upon the base sheet and having a ledge formed upon the lower edge thereof to support copy thereon; means mounted upon the copy sheet and engaging the slots in the base sheet to slidably connect said copy sheet to said base sheet and for limited vertical movement thereon; a horizontally disposed pasteboard line indicator movably superimposed upon said sheets and having tabs formed integrally therewith; upwardly inclined metallic points secured to said indicator for engaging said copy sheet to prevent movement of said indicator upwardly on said sheet; and similar upwardly inclined points on said tabs for engaging said base sheet and urged by the tension of said tabs, when the same are sprung beyond the plane of said indicator, to engage said base sheet and prevent upward movement of said indicator thereon.

15. A copy holder comprising a substantially upright pasteboard base sheet having vertically disposed slots therein; a similar pasteboard copy sheet superimposed upon the base sheet and having a ledge formed upon the lower edge thereof to support copy thereon; means mounted upon said copy sheet and engaging the slots in the base sheet for slidably connecting said copy sheet for limited vertical movement thereon; a horizontally disposed pasteboard line indicator movably superimposed upon said sheets and having tabs formed integrally therewith; upwardly inclined metallic points secured to said indicator for engaging said copy sheet to prevent upward movement of said indicator thereon; and similarly upwardly inclined points on said tabs for engaging said base sheet and urged by the tension of said tabs, when the same are sprung beyond the plane of said indicator, to engage said base sheet and prevent upward movement of said indicator thereon, and means for preventing lateral movement of copy on said copy sheet.
